TUMBLER

Robert A. O'Neil, Pittsburgh, Pa., assignor to Fesco, Inc.,
New York, N.Y., a corporation of Delaware

Filed July 8, 1965, Ser. No. 86,071

Term of patent 14 years

(Cl. D36—8)

I claim:

The ornamental design for a tumbler, as shown.
